UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

COMBINED TYPEWRITING AND CARD-PERFORATING MACHINE

Application filed July 1, 1926. Serial No. 119,838.

This invention relates to combined typewriting and card-perforating machines in which the type-operating keys of the typewriting machine are caused also to select punches, so that, at the completion of the line of typing on the work-sheet or card, a corresponding selection of punch-controllers is set up, preparatory to punching a card in correspondence with the typing on the same 10 card or on a separate work-sheet.

The typewriting machine includes a carriage, and the punch-selecting mechanism also includes a carriage, and both carriages have to be returned to begin a new line of 15 typing and punch-selecting. The carriages are motor-returned. The typewriter-carriage is returned by the same motor that is often provided in a typewriting machine for that purpose. It is usual to provide on the 20 keyboard of the typewriter a carriage-returning key for controlling said motor. One of the objects of the invention is to avoid the difficulty that would arise if the carriage-returning key were operated and the typewriter-carriage returned before the punching 25 of the card.

To avoid this difficulty, the usual carriage-returning key of the typewriter is temporarily diverted from performing its said function, and instead is connected to cause first 30 an operation of the punch-operating devices, so that the typewriter-carriage remains stationary at this time notwithstanding the manipulation of said carriage-returning key. Hence, there can be no carriage return prior 35 to the punching operation. A train of mechanism extends from said carriage-returning key to a constantly-revolving power-shaft of the punching mechanism, and 40 clutches said shaft to the selected punches to cause operation thereof.

A return train of mechanism extends from the punch-operating mechanism back to the typewriting mechanism, to effect automatically 45 a return of the typewriter-carriage under the power of said carriage-driving motor. Hence, the depression of the carriage-returning key of the typewriter first 50 effects the operation of the punches and then

causes operation of the carriage-return motor.

The typewriter-carriage and the punching-mechanism carriage are connected by a mechanical train, so that said motor returns both carriages to their starting points. During the returning, the punch-selecting devices are restored to normal positions. Thus, the operation of said key, which forms part of the typewriter-keyboard, causes a card-feeding and perforating cycle of the perforating mechanism, and then causes the typewriter-carriage and perforating-mechanism carriage to be returned to normal starting 55 positions.

Another feature of the invention is the 60 provision of means whereby all of the typewriter keys are locked and rendered inoperative during the entire interval in which the carriages are being returned. An advantage of this latter feature is that not only is blurring of the work-sheet by operating the type 65 keys while the carriage is in motion prevented, but errors which might be set up in the perforator setting mechanism by such inopportune operation of the type keys during the return of the carriages, are also 70 avoided.

The features of this invention are particularly useful in machines of the type shown in my co-pending application No. 48,723, filed 80 August 7, 1925 (now Patent No. 1,683,979, dated September 11, 1928), wherein a typewriter carriage is mechanically coupled to a perforator carriage so that both carriages move in unison, and wherein power driven 85 means to return the typewriter carriage are also provided as part of the typewriter equipment.

Such a machine to which the present invention is herein illustratively applied consists of the well-known Underwood typewriter having its carriage coupled to the carriage of a Powers key punch. The key punch, which will hereinafter be called the card perforator, is of the type shown in Patent No. 1,299,022 to J. Powers, dated April 1, 1919.

The card perforator includes a bank of punches and a bank of settable pins over the punches. The punches are arranged in the 190

- usual 45 columns by means of a card frame that includes a die plate and a stripper plate, the stripper plate guiding the lower ends of the punches and being separated from the die plate by a gap which may receive a card to be punched. The upper ends of the punches are guided by properly aligned holes in a fixed plate and have flanged heads which normally bear upon the fixed plate.
- 10 The card frame with the card is movable upwardly, and, during the upward movement of the frame and the card, the lower ends of the punches bear upon the surface of the card and the punches are thus carried upwardly toward the bank of settable pins. Wherever a hole is to be punched one of these pins has been set by depressing and latching it in its depressed position. The set pins oppose the upward movement of the corresponding punches which are thus caused to penetrate and perforate the card.
- 15 Immediately after the upward movement of the frame and card they are both retracted and the card is thereby stripped from the punches which may have penetrated it, the downward movement of the punches being arrested and limited by the aforementioned fixed plate.
- 20 Before the card may be punched the settable pins are set in one column at a time by means of a row of pin setting plungers, which moves from column to column in escapement controlled steps, each step following the operation of one of a number of plunger actuating keys.
- 25 To enable the row of pin setting plungers to traverse the bank of settable pins they are mounted in the usual carriage which is part of the perforator mechanism. According to my aforesaid co-pending application, this carriage moves in unison with the typewriter carriage by means of two racks and an intermediate pinion which couple the carriages. The pin setting plungers are actuated by corresponding electromagnets, which in turn are caused to be energized by the operation of the typewriter keys, which closes circuits for the magnets by means of contacts that underlie the keys.
- 30 The machine herein described, as an illustrative example to which the present invention may be applied, is used to type a heading on cards, the heading corresponding to perforations that are to be made in the card.
- 35 These perforated cards, as is well known, are used in making groupings, tabulations, etc., of the data represented by the perforations.
- 40 Simultaneously with the typing of the heading on a card, pins for the corresponding punches are set in the perforator mechanism, the perforator carriage moving step by step in unison with the typewriter carriage. After a line of data has been typed on a card the card is removed from the typewriter and presented against the usual card

feed rolls which carry the card into punching position.

These rolls rotate during a cycle of the perforator, and toward the end of the cycle after the card has been carried into punching position in the aforementioned gap of the card frame, the card frame is moved up and down to effect the punching of the card according to the pins that were set. After the card has been thus punched both carriages are returned by power-driven carriage-return mechanism, which is part of the Underwood typewriter.

Heretofore, one key has been used to initiate a cycle of the perforator to feed and punch the card, and then another key to engage the carriage-return mechanism. If the carriage-return key is inadvertently operated first, the carriages will be returned before the punching of the card has been effected and the setting of the pins in the perforator will be wiped out, because the perforator carriage in its return movement automatically causes the restoration of any pins that were set. Aside from this it is an advantage to avoid the necessity of thus operating two keys.

The present invention provides means whereby one key effects the perforator cycle and then the return of the carriages. Both functions, by means of the present invention, always occur in proper sequence.

There is provided, therefore, an operating key adjacent the typewriter keyboard and preferably mechanical connections from said key to the usual perforator drive-engaging means, whereby a perforator cycle may be initiated. During this cycle the usual power shaft of the perforator mechanism makes one revolution, during which, (according to this invention) it effects the punching and then causes the return of the typewriter-carriage and the punch-carriage.

The usual carriage-return mechanism of the typewriter is engaged by releasing the usual spring-pressed carriage-return engaging member. The release of this member causes the usual motor to be started and also causes a simultaneous engagement of the usual clutch, whereby the motor is enabled to drive the typewriter-carriage in its return movement and with it the perforator carriage. The release of this member is effected by a movable arm, the end of which, as it moves, trips the carriage-return engaging member. This movable arm heretofore has been operated by the so-called carriage-return key. In the present invention the movable arm is automatically caused to be actuated toward the end of the perforator cycle, after the perforator mechanism has operated to feed and punch a card. The means whereby this is accomplished consists preferably of a tappet on the aforesaid main shaft of the card perforator and rotatable

therewith, and a train of linkage connected to the aforesaid movable arm that releases the carriage-return engaging member. One end of this train of linkage is disposed to lie in the path of said tappet on the main shaft. Consequently said tappet, during a predetermined part of its revolution, is effective to displace the train of linkage and thereby actuate the movable arm and release the carriage-return engaging member.

The main shaft, as already stated, makes one revolution for every cycle of the perforator, and the angular initial position of the aforesaid tappet thereon with respect to the train of linkage which it displaces may be set so that the linkage is displaced at the proper time in the cycle. The rotation of the main shaft also actuates the card feed-rolls and the usual means for raising and lowering the card-frame. It will be understood that other suitable means brought into action during a perforator cycle may be used to automatically engage the carriage-return means, such other means being within the scope of the present invention.

The actuation of the usual perforator-drive engaging means is, as stated, preferably accomplished by means of mechanical connections from the operating key. The perforator-drive engaging means may be also actuated by the usual electro-magnet operated means controlled by the operating key in the usual manner to be illustrated and described.

The typewriter-keys are locked during the return movement of the carriages, by utilizing a key-lock train of the typewriter, partly illustrated herein, of the type shown in the Patent to W. F. Helmond, No. 775,331, dated November 22, 1904. This mechanism includes the key-lock-rod that is arranged transversely of the typewriter-key-levers and supported upon pivoted arms, whereby it is enabled to be swung into and out of locking relationship to the usual hook-like projections on the key-levers. The aforementioned carriage-return engaging member, when released, causes a displacement of the train of parts to effect engagement of the carriage-return mechanism, and, by suitable means which in the present embodiment of the invention consist mainly of a link between said train of parts and one of the key-lock-rod supporting arms, this displacement is effective to bring the key-lock-rod into locking relationship with the key-levers. This locking relationship is maintained throughout the return movement of the carriages. At the end of said movement the aforesaid train of parts is restored to normal position.

Other features and advantages will hereinafter appear.

In the accompanying drawings:

Figure 1 is a cross-sectional side elevation 65 of the combined typewriter and card-per-

forator, showing only such parts as are necessary to illustrate the invention.

Figure 2 is a top plan view of the combined typewriter and card-perforator.

Figure 3 is a front elevational view of the linkage from the operating key to the perforator-mechanism and the linkage, whereby the carriage-return mechanism is engaged.

Figure 4 is a side elevation, showing the relation of parts when the operating key is depressed.

Figure 5 is a cross-sectional side elevation of the card-perforator, showing details of the construction.

Figure 6 is a side elevational view, showing the relation of the parts when the cycle of the perforator-mechanism has caused the carriage-return mechanism to be engaged.

Figure 7 is a diagrammatic view of the electromagnet actuated means for initiating an operating cycle.

Figure 8 is a view indicating the usual Underwood spring motor and escapement mechanism.

As shown in the drawings (Figures 1 and 2) of the combined typewriting and card-perforating machine, a record card 10 is positioned around a platen 11 of an Underwood type-writer, so that type-bars 12 actuated by keys 13 through the usual type-actions, not shown, may print along a line near the upper edge of the card. The keys 13 are on the usual key-levers 14, partly shown in Figure 1. As the keys 13 are operated to print, a carriage 15, in which the platen 11 is mounted, moves in letter-feeding steps impelled by the usual spring-motor 16 and controlled by the usual Underwood escapement mechanism 17. The heading printed on the card is descriptive of items to be represented by holes that are to be punched in the card, the holes and their location in the card affording means whereby the cards may be used in the well-known processes of mechanical accounting.

Simultaneously with each operation of any key 13, a corresponding setting of the card perforator mechanism is effected, so that the aforesaid holes corresponding to the typed heading may be punched when the typing of the heading has been finished. For punching the holes the card perforator has 45 columns of punches 18. A side view of one of the columns of punches is included in Figure 5. The lower portions of the punches are guided by a plate 19 which is separated from a die-plate 20, by a gap which receives the card 10 for punching. The plate 19 and die-plate 20 are part of a card-frame 21 which is movable up and down in guides 22.

For selecting the punches there is provided over each column of punches 18 the usual column of settable pins 23. Wherever a punch is to punch a hole a pin is set by depressing the pin, and a spring-pressed latch-plate 24, of which there is one for each column

of pins, holds the set pin in its depressed position by means of a notch 25 formed in each pin. A selected punch reacts against the pin that is set for said punch, in the usual manner to be described to effect the punching of a hole. Each column of punches corresponds to a letter-space, and each punch by its position in the column represents a certain letter or numeral. Some of the characters printed are represented by two punch-positions in a column.

As the characters are typed on the card the corresponding punches are selected by setting the pins 23 in one column at a time as the carriage moves in letter-feeding steps. To set the pins there is provided a column of pin-setting plungers 26 which may register with any column of pins. Each plunger is movable downwardly by means of the usual bell-crank 30, to an arm 31 to which the upper end of the plunger is pivotally connected. Each bell-crank 30 is rotated to depress its plunger by means of the usual push-wire 33 contained in the flexible sheath 34, one end of 25 the push-wire pushing against a vertical arm 32 of the bell-crank.

When the typewriter-keys are operated these push-wires, of which there is one for each bell-crank 30, are actuated, by means of the usual solenoids, to rotate the bell-cranks. The solenoids, not shown, are contained in the casing 35, Figure 2. To enable the operation of any typewriter-key to energize a corresponding solenoid, there is provided for each key-lever 14 and operable thereby the usual contact device which is not shown but is contained in the casing 36, Figure 1. When a typewriter-key is operated the related contact device is operated to close one or more circuits to energize the corresponding solenoid or solenoids. Included in these different circuits are the wires from the contact devices in the typewriter to the solenoids of the card perforator, and these wires are gathered in the usual cable 39, Figure 1, that virtually connects the card perforator and the typewriter for joint operation.

To enable the pins 23 to be set in one column at a time, the pin-setting plungers 26 and related parts are mounted in a perforator-carriage 40, which traverses the bank of pins 23, the lower ends of the column of plungers 26 passing over the column of pins 23. The perforator-carriage 40 is guided by means of the usual rolls 41 and rails 42.

The perforator-carriage 40 is coupled to travel in unison with the typewriter-carriage, so that as a character is typed a pin or pins may be set for the column of punches corresponding to the letter-space on the card of the character typed. To couple the carriages there is provided, as shown in my aforesaid co-pending application No. 48,723, a rack 43 secured to the perforator-carriage 40 by means of brackets 44, and a similar rack 45

secured to the typewriter-carriage 15 by means of brackets 46. A pinion 47 suitably mounted, as shown in Figure 1, meshes with each rack, and by means of said racks and pinion which are always in mesh, the perforator-carriage moves in unison with the typewriter-carriage both in letter-feeding and return directions.

When the typing of the line of data on the card is finished the card is removed from the typewriter by turning the platen with the card counterclockwise, and sliding the card when free of the platen over the table surfaces 48 and 49 into guides 50 (Figure 2) by means of which the card is properly directed toward the first pair of feed-rolls 51. The card having been presented to the feed-rolls so that they are ready to grasp and advance it, as shown in Figure 5, an operating cycle of the perforator is initiated. During the first portion of this cycle the rolls 51 and other rolls 52 in train therewith advance the card into punching position within the aforementioned gap in the card-frame 21. The proper punching position of the card is determined by a movable stop 54, which is in position to intercept the leading edge of the card and thereby arrest a further movement thereof. The upper rolls 53 are lightly spring-pressed upon the card and the corresponding lower rolls 53^a slip idly over its surface when the card is thus arrested.

The feeding of the card into punching position is done, as stated, during the first portion of the operating cycle of the card perforator. During said cycle a main shaft 55 makes one revolution. By means of the usual gearing indicated in Figure 5 this main shaft 55 drives the rolls 51, 52 and 53, the rolls 53^a, as stated, slipping idly over the surface of the card after it has been arrested by the movable stop 54. During this first portion of an operating cycle a card, left in punching position, at the conclusion of a preceding cycle, is conveyed to a receptacle 56 by rolls 57 that are in train with the other rolls. During this passage of a card to said receptacle the movable stop 54 is caused to be withdrawn for a time long enough to permit said passage.

During the final portion of the operating cycle an upward movement of the card frame 21 with the card therein causes all the punches, except those punches over which a pin is set, to be pushed upwardly in an idle movement with the card. Wherever a pin is set the upward movement of the corresponding punch with the card is opposed by the set pin, and the punch reacting against the set pin is thereby caused to penetrate and perforate the card.

Immediately after its upward movement the card frame moves downwardly and returns to its normal position. During this downward movement the card is stripped from the punches which have penetrated it.

Each of the punches 18 has a head 18^a, the under surface of which reacts against a fixed plate 58 while the card is being stripped from the punch. The fixed plate 58 also guides the 5 upward portion of the punches by means of properly aligned holes therein.

The upward and downward movement of the card frame 21 is derived from the rotation of the main shaft 55 by means of the 10 usual cam 59, and the usual pivoted frame 60 consisting of a cross-bar 61 with an arm 62 at each end and an arm 63 intermediate said ends. The cam 59 is fastened to the main shaft 55, and its contour is formed to move 15 the frame 60, and consequently the card frame 21, up and down during the final portion of the operating cycle.

To initiate an operating cycle, which is equivalent to a revolution of the main shaft 20 55, there is provided the usual perforator drive engaging means which are of the type shown in Patent No. 1,352,006 to W. W. Lasker, dated September 7, 1920. Said means include a driving disk 65 keyed to a continuously rotatable power driven shaft 66 which is substantially in line with the main shaft 55. The disk 65 has a number of driving spurs 67, any one of which may co-act with a projection from the main shaft 55 to drive 30 said main shaft. This projection is in the form of a retractable pin 68 which is normally held disengaged from the spurs 67 of the disk 65 which rotates idly when not driving the card perforator in an operating cycle. 35 The pin 68 is held in proper relation to the driving disk 65 by means of the usual arm 69 keyed to the main shaft 55. To hold the pin 68 said arm is provided with a counter-bored hole which fits the pin and forms a 40 seat through which a shank 70 of the pin passes. The usual spring 71 (Figure 2) urges the pin to move into engagement with the driving spurs 67.

To normally hold the pin 68 disengaged 45 from said spurs 67 and also to disengage the pins from said spurs toward the end of an operating cycle, there is provided the usual cam lever 72 against which a head 73, formed on the shank of the pin, reacts. The cam lever 72 is pivotally supported at 74 by a post 75. It will be seen that the pin 68 is freed 50 and escapes to move into engagement with one of the spurs 67 if the cam lever receives an impulse that causes it to be withdrawn for a 55 moment from the head 73 of the pin.

Included in the usual means for imparting this impulse or movement to the cam lever 72 is the link 76 pivotally connected to the cam lever at 77. Said link 76 is slidably 60 guided at one end in a slot closed by a pin 78, said pin and said slot being at the upper end of an upright fixture 79. Another slotted fixture 80 guides the other end of said link 76 laterally and is extended downwardly to 65 hold one end of a restoring spring 81 which

is attached to said link and serves to restore and hold said link 76 and cam lever 72 in normal position.

The usual means described in my aforesaid co-pending application No. 48,723 for actuating the link 76 to initiate a perforating cycle, are shown diagrammatically in Figure 7 and include a lever 84 pivoted at 85 to the perforator frame. To translate a movement of said lever into a substantially endwise movement of the link 76, a pin 86 in said link is provided and co-acts with an inclined cam slot 87 which is formed at the end of the upper arm 88 of said lever. It will be seen that a sufficient clockwise displacement of the lever 84 about its pivot will cause a corresponding endwise displacement of the link 76. To effect said displacement of the lever 84 the lower arm thereof is pushed by one end of the usual push wire 83 which in turn is pushed at the other end by the plunger 89 of a solenoid 90 which is contained in the casing 35. A circuit to cause the solenoid to be energized may be made by means of contacts 91 which are controlled by a key 92 at 90 the typewriter keyboard.

It is one purpose, however, of the present invention to provide that the link 76 may be actuated by means of mechanical connections, from a key at or near the typewriter keyboard. One advantage of such mechanical connections is that their action is more direct and therefore more positive than electrically operated connections. Another advantage is that mechanical connections cost 95 relatively less to manufacture and maintain. Still another advantage is that some of the parts of the mechanical connections between a key at the typewriter keyboard and the link 76 may be made of parts that are duplicates 100 of or identical with the parts used in another feature of the invention, namely, the parts which constitute the means whereby the carriage-return mechanism is engaged at the 105 end of an operating cycle of the card perforator.

The usual Underwood carriage-return mechanism has an electric driving motor 95 supported by the typewriter frame 96. By means of the usual gearing housed in the 110 casing 97 said motor is connected to a shaft 98, to which is secured a driving clutch member 99.

To enable the rotation of the clutch member 99 to drive the typewriter carriage 15 in a return movement, there is secured to said carriage the usual rack 100 which meshes with a pinion 102. Said pinion 102 is formed on another clutch member 103 which is slidably into and out of engagement with the clutch member 99 along an extension of the shaft 98. It will be seen that when said clutch members interlock the motor 95 can drive the typewriter carriage and the punch-selecting carriage. To enable the clutch 120 125 130

member 103 to be brought into engagement with the clutch member 99 by means controllable from a point near the typewriter keyboard, there is provided the usual train 5 of linkage 104. One end of said train is connected in the usual manner to the clutch member 103, and at the other end of said train is a bar 105, which projects through a front plate 109 of the typewriter near its 10 left hand side. In the normal position of said train of linkage the clutch members 99 and 103 are disengaged as shown in Figure 1. Said normal position is secured against the pull of a spring 106 by means of a latching 15 edge formed by a notch 107 in the bar 105, said latching edge coacting with the lower edge of a slot 108 in the front plate 109 of the typewriter.

To cause engagement of the clutch members 99 and 103 so that the motor 95 may return the typewriter carriage, the forward part of the bar 105 is slightly lifted. This permits the holding edge formed by the notch 107 to escape from the front plate 109.

20 The pull of the spring 106 then displaces the train of linkage 104 and the engagement of said clutch members, as shown in Figure 6, is thereby effected. Simultaneously with the displacement of said train of linkage the usual switch contained in the case 110 is closed and the driving motor 95 thereby started. The closing of the switch is effected by the movement of a bar 101 connected, as shown, to the train of linkage 104.

25 To enable the carriage 15 to automatically terminate its return movement when it has reached a predetermined position, the usual means are provided to disengage the clutch members 99 and 103 and open the aforesaid switch to stop the motor 95. Said means include an extension of the aforesaid train of linkage 104, said extension including the linkage 111 and terminating in a cam-shaped end of a dog 112, keyed to a splined 30 rockable shaft 113. Said dog 112 is movable along said shaft with a right hand marginal carriage stop 114 (Figure 1).

When the typewriter carriage in a power 35 driven return movement reaches a position determined by said carriage stop 114, a tappet 115 on said carriage displaces the cam-shaped end of the dog 112, and thereby effects the restoration of all parts in train with said dog to normal. In this restoration 40 the clutch members 99 and 103 are disengaged and the switch in the case 110 is opened to stop the motor 95. Thus is the power driven return movement of the typewriter and 45 punch-selecting carriages automatically arrested.

During the return movement of the perforator carriage 40, which is driven by the typewriter carriage, all the pins 23 which 50 were set are automatically caused to be restored by said movement. To thus effect said

restoration the usual means described in my aforesaid co-pending application No. 48, 723 are used. Said means include, for each column of settable pins, a releasing lever 27 (Figure 5) which the perforator carriage in its return movement displaces by means of a roll 28 on said perforator carriage, which is automatically brought into position so as to effect such displacement during said return movement. The displacement of the lever 27 in turn causes a longitudinal displacement of the corresponding latch plate 24 which is effective to release any pin 23 held by said latch plate. Any pin 23 when released is pushed upwardly by means of the usual spring 29. The settable pins 23 are guided in the usual stationary frames 93 and 94, the frame 93 also slidably supporting the latch plates 24.

To engage the carriage-return mechanism by raising the forward end of the bar 105 and thus releasing it in the manner described, there is provided a lever 117, which, in a clockwise rotation thereof, is effective to raise the forward end of said bar 105. To enable 50 said lever 117 to raise said bar, an end 118 of said lever engages a projection 119 of a block 120 that is pivoted on the side of said bar 105 at 121 and has a counter-weight portion 122, which normally keeps it against a stop-pin 123. The pivoted block 120 is provided so that a retractive movement of the lever 117 is ineffective to raise the bar 105. Heretofore the lever 117 has been actuated by means of a key attached to an extension 55 of said lever, as shown in my aforesaid co-pending application No. 48,723. For automatically line-spacing the platen 11 during a power driven return movement of the carriage there may be provided the usual means, not shown. Said last mentioned means may be of the type shown in my co-pending application, Serial No. 41,507, filed July 6, 1925. (now Patent No. 1,679,727, dated August 7, 1928).

According to the present invention, and, in order that a power-driven return movement of the carriages shall be initiated automatically after a card-perforator cycle, in an operating cycle thereof, has effected feeding and punching of the card, there are provided means whereby the final part of a revolution of the main shaft 55 of the card perforator will operate the lever 117 to initiate said return movement. Said means in the illustrated form of the invention includes a lever 125 pivoted to a fixture 126 at 127, said fixture being secured to the perforator-frame, and also includes the connections whereby a movement of said lever 125 is 115 transmitted to the lever 117 as a carriage-return initiating impulse. The movement of the lever 125 is derived from the rotation of the main shaft 55 by means of tappet 129 that is formed on the end of the arm 69, said 120 125

movement occurring as said tappet displaces an end 130 of the lever 125. The aforesaid connections from the lever 125 to the lever 117 include a bell-crank-lever 131 pivoted on a fulcrum rod 124 in a bracket 132 that is fastened to the under side of a platform 133, on which the typewriter is mounted. Another part of said connections is the lever 134 that is pivoted in a bracket 135 fastened to the frame of the card-perforator. The lever 125 is connected to the lever 134 by a link 136, the lever 134 in turn being connected to the bell-crank 131 by a link 137. A link 138 finally connects the bell-crank 131 to the lever 117.

In order that the lever 117 shall release the bar 105 at what is substantially the end of a revolution of the main shaft 55, the initial normal position of said lever in relation to said bar, with a corresponding normal position of the train of parts connected to said lever 117, is substantially as shown in Figure 1. This initial position is held against the pull of a spring 139 which is provided to retract the lever 117 and its train of parts, one end of said spring being conveniently applied to the link 137 and the other end being anchored to a bracket 140 fastened to the under side of the platform 133. To hold said initial position against the pull of said spring, the corresponding initial position of the tappet 129 on the arm 69 of the main shaft 55 of the card perforator is as shown in Figure 1. In this position the pull of said spring reacts, through the lever 125, upon said tappet.

At the beginning of a revolution of the main shaft 55 in an operating cycle, the tappet 129 over-rides the end 130 of the lever 125. As said tappet 129 escapes, the train of parts actuated by said lever 125 assumes a position, shown in Figure 4, under the influence of the spring 139. This position is determined by a stop-pin 141 against which the lever 125 strikes. During the final part of the revolution of the main shaft 55 the tappet 129 displaces the end 130 of the lever 125, and thereby rotates said lever counter-clockwise to its original position, as shown in Figure 6. A corresponding rotation is transmitted, as stated, to the lever 117 which, in the manner described, initiates a return movement of the carriages.

To initiate an operating cycle of the card-perforator, the link 76 is actuated to cause the withdrawal of the cam-lever 72 from the head 73 of the pin 68. To thus actuate said link 76 by means controllable from a point near the typewriter keyboard, there is provided at the side of the keyboard and upon the same fulcrum that supports the lever 117, a lever 143. For operating said lever 143 manually, a key 144, attached to said lever 143, is provided.

The lever 143 is supported, as shown in

Figure 3, within the typewriter frame on a bushing 142 which serves as a nut for securing a stud 145 upon which the lever 117 is pivoted. Thus it will be seen from Figure 3 that levers 117 and 143 are mounted upon virtually the same fulcrum, but on opposite sides of the typewriter frame. An extension 151 from the lever 143 is directed to the outer side of said typewriter frame, so that the key 144, located outside of said frame, may be thereby attached to said lever.

In order that operation of said key 144 shall be transmitted to the link 76 as an operating cycle initiating impulse, a train of simple mechanical connections is provided between said key 144 and said link 76. Said train includes a bell-crank 146 that is pivoted upon the same fulcrum rod 124 upon which the bell-crank 131 is mounted in the bracket 132. Connecting said bell-crank 146 to the lever 143 is a link 147. Upon the same fulcrum on which is pivoted the lever 143 there is pivoted a lever 148 for actuating the link 76, said lever 148 being connected at its upper end to said link 76 by means of a pin-and-slot connection 149. A link 150, similar to the link 137, connects the lever 148 to the bell-crank 146. The train of parts beginning with the key 144 and ending with the cam-lever 72 is held in normal position by the pull of a spring 152, one end of which is conveniently applied to the link 150. The other end of said spring 152, like the spring 139, is attached to the bracket 140. A stop-pin 154 driven into the typewriter side frame may be provided to limit the downward stroke of the key 144, as shown in Figure 4. The links 137 and 150 are offset, as shown in Figure 2 on account of the offset positions of the parts which each link connects.

During the return movement of the carriages, operation of all the typewriter keys and key-levers is to be prevented, for reasons already set forth. Each of the key-levers 14 has the usual hook-shaped locking projection 155. Coacting with said hook-shaped projection when the keys are to be locked, is the usual key-lock rod 156, which is part of the regular Underwood key-lock mechanism. Said key-lock rod is supported at each end by an arm 157 and its intermediate portion is supported by an arm, not shown. The arms 157 rotate with a shaft 158, pivoted between the typewriter side frames. The usual spring 159 normally holds the key-lock rod 156 in position, shown in Figure 1.

For causing the key-lock rod 156 to be in locking relationship with the key-levers 14 during the return of the carriages, there are provided means whereby said locking relationship is effected concurrently with the displacement of the aforementioned train of linkage 104. To this end there is provided a link 160 which connects said train of linkage 104 to an arm 157, which with a paired

arm supports the key-lock rod 156. It will be seen that as said train of linkage 104 is displaced the key-lock rod 156 will move into locking relationship with the key-levers 14, as shown in Figure 6. In order that the key-lock rod 156 may be actuated by the usual carriage controlled means (not shown) independently of the link 160, said link 160 is connected to the arm 157 by means of a pin-and-slot connection 161.

As shown in Figure 1, a portion of the connecting linkage between the typewriter and the card perforator is below the platform 133 which supports the typewriter. As a guard for the portion of the linkage which is below said platform there is provided a casing 162. Said casing may be formed, as shown, so as to be as close to the platform 133 as possible in order not to interfere with the knees of an operator. In certain other arrangements of the contacts which are contained in the casing 36 below the typewriter keyboard, the contacts are incorporated in a unit which is fastened below the platform 133. An outline of said unit would be indicated by the dotted line 163, Figure 1. Where such a unit is used the casing 162 should have an asbestos lining 164, so that said casing is protected from sparks or other hazards which may be incidental to the operation of the contacts and other electrical devices in said unit.

A card 10 is inserted into the typewriting machine around the platen 11, whereupon, by means of keys 13, types 12 are operated to cause one line to be typed on the card. The depression of each key 13 in the typewriter keyboard, besides swinging its corresponding type to print against the platen 11, simultaneously by means of an electric connection operates one of the series of Bowden wires 33 on the Powers machine, to swing plunger 31-26, which in turn sets up a pin 23, which will later on co-operate with the corresponding punch 18 to make a hole in card 10. The operation of the keys 13 also feeds the typewriter-carriage and the punch-selecting carriage in unison, as the carriages are connected through the racks 43 and 45.

After one line is typed on the card, and the corresponding pins 23 are set, the card is removed from the typewriting machine and slid to a position shown in Figure 5, so that feed-rolls 51, 52 of the punching mechanism may, when revolved, feed the card under the punches 18.

It will now be realized that the card 10 will first be fed under the punches and punched, and then fed out into the container 56, prior to the returning of the typewriter-carriage and punch-selecting carriage, inasmuch as the return motion of the latter carriage restores the punches to their normal positions. The present invention provides means for feeding the card under the punching pins, then punching the card, and then

feeding it out of the machine, prior to returning the two carriages. For this purpose, the special key 144, which would now come into play, is so connected that, when operated, it will not actuate any of the typewriter-carriage-return mechanism, but the depression of said key 144 will merely close the clutch, being for this purpose caused to depress the link 147, which in turn will operate the bell-crank 146, moving the link 150 forwardly to swing the clutch-releasing arm 148 about its pivot, which will move the cam-link 76 rearwardly and cause the clutch-controlling cam 72 to be swung away from the clutch-pin 68 and allow said clutch-pin to move forwardly to project into the path of the constantly revolving punch-operating disk 67, to have the card punched prior to the return of the carriages.

It will thus be understood that nothing happens to either the typewriting machine or the punching machine until one of said clutch projections on the disk 67 engages the pin 68 and starts to revolve the operating arm 69, on which the pin 68 is mounted, the feed-rolls 51, 52, etc., now feeding the card onto a table or platform 21 (Figure 5) under the punches. Then the revolving cam 59 swings the member 60 to raise and lower said card-platform 21 and cause the card 10 to be punched, after which the card feeds out.

The initial movement of arm 69 sets the bell-crank 118 for operating the tripper 119 of the typewriter-carriage-return mechanism. This setting is done by the projection 129 on said arm passing the end 130 of the lever 125 which allows said lever 125 to be swung by spring 139, to operate the train of linkages 136, 134, 137, 131, 138, and cause the bell-crank 117-118 to be moved to a position shown in Figure 4 in back of the typewriter-carriage-return tripper 119. At this point, the bell-crank 118 remains until the power-disk 67 has carried the clutch-pin 68 and arm 69 completely around, at which time the projection 129 engages the arm 130 of the bell-crank 125 and moves the train of links 136, 134, 137, 131, 138 in the opposite direction so as to cause the bell-crank 118 to engage the tripper 120-119 and set off the carriage-return mechanism of the typewriting machine. This restores the carriage of the typewriter together with the carriage of the punching mechanism, and the restoring of the punching carriage restores all the punches to their normal position. A new card can now be inserted into the typewriting machine and the operation repeated.

It will be seen that in the carriage-returning train, governed by key 144, there is connected the punch-operating mechanism, so that after typing a line, the operator will not return the carriage without intervening operation of the punches by said mechanism included in said train.

Variations may be resorted to within the scope of the invention, and portions of the improvements may be used without others.

Having thus described my invention, I claim:

5. 1. In a combined typewriting and card-perforating machine, the combination with perforating mechanism operative through a cycle of operations for which typing operations are preparatory and precedent, of a driver for said mechanism normally disconnected therefrom, coupling means for effecting said connection, a non-typing key remote from said means to control a certain typewriting operation, a train of linkages whereby the operation of said key will cause said coupling means to engage with the driver to actuate the perforating mechanism through said cycle of operations, and means associated with said coupling means to initiate the performance of said typing operation. 70
10. 2. In a combined typewriting and card-perforating machine, the combination with perforating mechanism operative to punch a card for which typing operations are preparatory and precedent, of a driver for said mechanism connectible therewith but normally disconnected therefrom, mechanically-tripped coupling means for effecting said connection, a non-typing key to control a certain typewriting operation, a train of linkages whereby the operation of said key will cause said coupling means to trip and engage with the driver to actuate the perforating mechanism to punch the card, a second train of linkages, and means associated with said coupling means to engage with said second train of linkages upon the completing of the card-punching operation to initiate the performance of said typewriting operation. 75
15. 3. In a combined typewriting and card-perforating machine, the combination with perforating mechanism operative through a cycle of operations for which typing operations are preparatory and precedent, of a driver for said mechanism normally disconnected therefrom, coupling means for effecting said connection, a non-typing key to control a certain typewriting operation, a train of linkages whereby the operation of said key is mechanically transmitted as an impulse to said coupling means to engage the same with the driver to actuate the perforating mechanism through said operations, and mechanical means associated with said coupling means to initiate the performance of said typing operation. 80
20. 4. The combination with a typewriter and card-perforator coupled for joint operation, said perforator including a motor and a clutch, of means actuatable to effect the engagement of said clutch with the motor to drive the perforator, a non-typing typewriter-key to control a certain typewriting operation, 85
25. linkages connected to said key, whereby the operation of the key actuates said means to engage the perforator with the motor to operate to punch a card, and additional linkages connecting said perforator with the typewriter effective upon the completion of the punching operation to initiate said typewriting operation. 90
30. 5. In a combined typewriting and card-perforating machine having movable carriages, the combination with engageable carriage-return mechanism, of perforating mechanism, and means for operating the perforating mechanism, and means whereby said perforator operating means are enabled to automatically engage said carriage-return mechanism. 95
35. 6. In a combined typewriting and card-perforating machine having movable carriages, the combination with engageable carriage-return mechanism, perforating mechanism, and means for actuating the perforating mechanism in an operating cycle thereof, of means whereby said carriage-return mechanism is automatically engaged at the end of said operating cycle. 100
40. 7. In a combined typewriting and card-perforating machine having movable carriages, the combination with engageable carriage-return mechanism, perforating mechanism, and means for actuating the perforating mechanism in an operating cycle wherein a card is fed into position and punched, of means whereby said carriage-return mechanism is automatically engaged during said cycle after said card has been fed into position and punched. 105
45. 8. In a combined typewriting and card-perforating machine having a typewriter carriage coupled to a perforator carriage so that both carriages move in unison, the combination with engageable carriage-return mechanism for said typewriter carriage, of perforating mechanism means for operating the perforating mechanism in an operating cycle, and means whereby said carriage-return mechanism is automatically engaged during said cycle, to return said carriages. 110
50. 9. The combination with a typewriter and a card perforator coupled for joint operation, said typewriter having a letter-feeding carriage and said perforator having a carriage coupled to and driven by the letter-feeding carriage on said typewriter, engageable carriage-return mechanism on said typewriter, and means whereby said perforator is actuated in an operating cycle, of means whereby said carriage-return mechanism is automatically engaged during said cycle to return said carriages. 115
55. 10. The combination with a typewriter and a card perforator coupled for joint operation, said typewriter having a letter-feeding carriage and said perforator having a carriage coupled to and driven by the letter- 120
60. 125
65. 130

feeding carriage on said typewriter, engageable carriage-return mechanism on said typewriter, and means whereby said perforator is actuated in an operating cycle, of means for initiating said cycle, and means whereby said carriage-return mechanism is automatically engaged during said cycle to return said carriages.

11. The combination with a typewriter and a card perforator coupled for joint operation, said typewriter having a letter-feeding carriage and said perforator having a carriage coupled to and driven by the letter-feeding carriage on said typewriter, engageable carriage-return means on said typewriter, and means whereby said perforator is actuated in an operating cycle, of a key on said typewriter, means whereby the operation of said key initiates said cycle, and means whereby said carriage-return mechanism is automatically engaged during said cycle to return said carriages.

12. The combination with a typewriter and a card perforator coupled for joint operation, said typewriter having a letter-feeding carriage and said perforator having a carriage coupled to and driven by the letter-feeding carriage on said typewriter, engageable carriage-return mechanism on said typewriter, and a member on said perforator actuatable to cause the initiation of an operating cycle of said perforator, of a key on said typewriter, means whereby the operation of said key actuates said member, and means whereby said carriage-return mechanism is automatically engaged during said cycle.

13. The combination with a typewriter and a card perforator coupled for joint operation, said typewriter having a letter-feeding carriage and said perforator having a carriage coupled to and driven by the letter-feeding carriage on said typewriter, engageable carriage-return mechanism on said typewriter, and a member on said perforator actuatable to cause the initiation of an operating cycle of said perforator to feed and punch a card, of a key on said typewriter, means whereby the operation of said key actuates said member for an ensuing cycle, and means whereby said carriage-return mechanism is automatically engaged and said carriages are returned as a result of said cycle after the feeding and punching of said card have been effected.

14. The combination with a typewriter and a card perforator coupled for joint operation, said typewriter having a letter-feeding carriage and said perforator having perforator setting mechanism including a carriage coupled to and driven by the letter-feeding carriage on said typewriter, means whereby a return movement of the perforator carriage causes a restoration of said setting mechanism, engageable carriage-return mechanism on said typewriter, and a

member on said perforator actuatable to cause the initiation of an operating cycle of said perforator to feed and punch a card, of a key on said typewriter, means whereby the operation of said key actuates said member for an ensuing cycle, and means whereby said carriage-return mechanism is automatically engaged, with a consequent return of said carriages and restoration of said setting mechanism as a result of said cycle after the feeding and punching of said card have been effected.

15. The combination with a typewriter and a card perforator coupled for joint operation, said typewriter having a letter-feeding carriage and said perforator having a carriage coupled to and driven by the letter-feeding carriage on said typewriter, carriage-return mechanism on said typewriter, and a member on said perforator actuatable to initiate an operating cycle of said perforator, of an element on said typewriter actuatable to engage said carriage-return mechanism, a key on said typewriter, mechanical connecting means between said key and said member whereby the operation of said key actuates said member, a tappet on said perforator, and means whereby said tappet during said cycle actuates said element to engage said carriage-return mechanism.

16. The combination with a typewriter and a card perforator coupled for joint operation, said typewriter having a letter-feeding carriage and said perforator having a carriage coupled to and driven by the letter-feeding carriage on said typewriter, carriage-return mechanism on said typewriter, and a member on said perforator actuatable to initiate an operating cycle of said perforator, of an element on said typewriter actuatable to engage said carriage-return mechanism, a key on said typewriter, a tappet on said perforator, a platform on which said typewriter is supported, linkage whereby said tappet may actuate said element, and linkage whereby said key may actuate said member, said linkages being disposed so that a substantial portion thereof is below said platform.

17. The combination with a typewriter and a card perforator coupled for joint operation, said perforator having a carriage coupled to and driven by a carriage on said typewriter, keys on said typewriter operable to print and also to set said perforator, and key-locking mechanism on said typewriter including a locking element movable into position to lock said keys at the end of a writing line, of engageable carriage-return mechanism to drive said carriages in a return movement, and means whereby said locking element is caused to be in position to lock said keys during said return movement, said means being constructed and arranged that said locking element is movable into locking

position independently of said means at the end of a writing line.

18. In a combined typewriting and card-perforating machine including a typewriter-carriage, the combination with a motor for returning said carriage, of perforator-mechanism, a member actuatable to cause the initiation of an operating cycle of said perforator-mechanism, a key at the typewriter keyboard, an operating train extending from said key to said member, and means automatically brought into action at the conclusion of such operating cycle for causing said motor to return said carriage.

19. The combination with a typewriter and a card-perforator, coupled for joint operation in which typing is done preparatory to and precedes an operation of the perforator to punch the data typed, and a trip member of said perforator actuatable to cause said operation of said perforator, of a key on said typewriter, mechanical connecting means between said key and said trip member, whereby the operation of said key is transmitted to said trip member as an impulse to actuate said member, and means to enable the perforating mechanism to control a typewriting operation.

20. The combination with a typewriter and a card-perforator, coupled for joint operation in which typing is done preparatory to and precedes an operation of the perforator to punch the data typed, and a member displaceable to cause said operation of said perforator, of a key on said typewriter, mechanical connecting means between said key and said member, whereby the operation of said key displaces said member to cause said operation of said perforator, and means to enable the perforating mechanism to control a typewriting operation.

21. The combination with a typewriting mechanism including a carriage and a carriage-returning motor, of a card-perforating mechanism, said typewriting and perforating mechanisms coupled for joint operation in which typing is done preparatory to punching the data typed, a member displaceable to cause a cycle of operations of said perforating mechanism to effect said punching, a carriage-returning key provided upon said typewriting mechanism, mechanical connecting means extending from said key to said member, whereby the operation of said key displaces said member to cause said operation of said perforating mechanism, and means controlled by said perforating mechanism to cause the return of said typewriter-carriage.

22. The combination with a typewriting mechanism and a card-perforating mechanism coupled for joint operation in which typing is done preparatory to punching the data typed, of a member actuatable to cause a cycle of operations of said perforating

mechanism to effect said punching, said typewriting mechanism including type-keys and also including a special non-typing key for controlling an operation of the typewriter, and connecting means extending from said special key to said perforating mechanism to cause a cycle of operations thereof, said perforating mechanism having means for automatically, and in predetermined sequence with said cycle of operations, causing the non-typing typewriting operation intended to be controlled by said key.

23. In a combined typewriting and card-perforating machine having movable carriages, the combination with power-driven carriage-return mechanism, of perforating mechanism, means for operating the perforating mechanism to punch, and means whereby the perforating mechanism operating means control the engagement of said carriage-return mechanism.

24. In a combined typewriting and card-perforating machine having movable carriages, the combination with power-driven carriage-return mechanism and means operable to initiate operation of said carriage-return mechanism, of perforating mechanism, means for operating said perforating mechanism to punch, and means whereby an operation of said perforating mechanism to punch is constrained to precede a return of said carriages initiated by said first-mentioned means.

25. In a combined typewriter and card-perforating machine having a typing carriage and a perforator-carriage, the combination with carriage-return mechanism effective to return both carriages, perforating mechanism, and means for actuating the perforating mechanism in an operating cycle wherein a card is punched, of means whereby the operation of said carriage-return mechanism is controlled by and depends on the perforating mechanism operating means to thereby preclude the return of the carriages before the completion of the punching operation.

26. In a combined typewriting and card-perforating machine including a typewriter having type-keys and a typing carriage, and a card-perforator having denominational punch-indexing devices and a carriage cooperative to set said devices in an advance movement and restore said devices in a return movement, the combination with an electric cable coupling said typewriter and perforator for joint operation of said type-keys and indexing devices, said machine having means whereby said carriages advance in consonance with said joint operation, of carriage-return mechanism including a key operable to effect the return of both carriages, and controlling means whereby said key even though operated does not become effective to return the carriages before

the completion of the punching operation for which the advance of said carriages was preparatory, thereby to preclude premature restoration of the indexing devices.

5 27. In a combined typewriting and card-perforating machine including a typewriter having type-keys and a typing carriage, and a card-perforator having denominational punch-indexing devices and a carriage co-operative to set said devices in an advance movement and restore said devices in a return movement, the combination with an electric cable coupling said typewriter and perforator for joint operation of said type-keys and indexing devices, said machine having means whereby said carriages advance in consonance with said joint operation, of carriage-return mechanism operable to effect the return of both carriages, perforator-actuating means for operating the perforator to punch according to the set indexing devices, a control-key, means whereby said perforator-actuating means are called into action by said key, and means whereby the carriage-return mechanism is automatically operated to return both carriages as a result of operating the perforator to punch, said key thus controlling the perforator-actuating means and also controlling the return of the typing carriage and of the perforator-carriage.

28. In a combined typewriting and card-perforating machine including a typewriter having type-keys and a typing carriage, a card-perforator having denominational punch-indexing devices, and means enabling the punch-indexing devices to be controlled denominational in consonance with the movements of the typing carriage, the combination with an electric cable coupling said typewriter and perforator for joint operation of said type-keys and indexing devices, of means operative in a return movement of said carriage to restore said indexing devices, and means whereby the perforator is operated to punch according to the set indexing devices and said typing carriage is automatically returned and the indexing devices are restored subsequently to and as a result of the punching operation of the card-perforator.

29. In a combined typewriting and card-perforating machine, the combination with a typing carriage, punches, punch-indexing elements including a punch-denomination-determining carriage, means whereby the advance of the punch-carriage is controlled in consonance with the advance of the typing carriage in a typing operation and whereby punch-indexing elements are set according to said typing operation, punch-operating means, carriage-return mechanism effective to return both carriages, and restoring means for the punch-indexing elements, of a single control-key, and means whereby the opera-

tion of said key effects operation of the punch-operating means, operation of said carriage-return mechanism to return both carriages, and also effects operation of the indexing element-restoring means.

30. In a combined typewriting and card-perforating machine, the combination with a typing carriage, punches, punch-indexing elements including a punch-denomination-determining carriage, means whereby the advance of the punch-carriage is controlled in consonance with the advance of the typing carriage in a typing operation and whereby punch-indexing elements are set according to said typing operation, punch-operating means, and carriage-return mechanism effective to return both carriages, of a single control-key, and means whereby operation of said key effects operation of the punch-operating means and also effects operation of said carriage-return mechanism to return both carriages.

31. In a combined typewriting and card-perforating machine, the combination with typing mechanism including a typing carriage, perforating mechanism including a denomination-determining carriage, and means whereby concomitantly with the operation of the typing mechanism the perforating mechanism is set preparatory to punching a record of the data typed and whereby, therefore, both of said carriages advance in consonance, of means for operating the set perforating mechanism to punch, carriage-return mechanism for returning both carriages, restoring means for wiping out the setting of the perforating mechanism, and two controlling devices each having a member which may be tripped for calling its respective device into action, one controlling device operable to effect the operation of the punching means, the operation of the carriage-return mechanism and the operation of the restoring means for wiping out said setting, and the other controlling device operable to effect only the operation of the carriage-return mechanism and the operation of said restoring means for wiping out said setting.

32. In a combined typewriting and card-perforating machine, the combination with typing mechanism including a typing carriage, perforating mechanism including a denomination-determining carriage, and means whereby concomitantly with the operation of the typing mechanism the perforating mechanism is set preparatory to punching a record of the data typed and whereby, therefore, both of said carriages advance in consonance, of a typewriter-keyboard, and two individually-operable tripping devices at said keyboard, one tripping device having connections effective when said one device is tripped for causing the operation of the set perforating mechanism to punch, the return of both carriages and the wiping out of the set-

ting of the perforating mechanism, the other tripping device having connections effective when said other device is tripped for causing only the return of both carriages and the wiping out of the setting of the perforating mechanism.

33. The combination with a typewriter and a card-perforator coupled for joint operation, said typewriter having a carriage and engageable power-driven carriage-return mechanism, said perforator operable in a cycle of punching operations for which a typing operation with an accompanying advance of said carriage is preparatory and precedent, of means becoming effective during and as a result of said cycle, whereby said carriage-return mechanism is automatically engaged to return said typewriter-carriage.

34. The combination with a typewriter and a card-perforator coupled for joint operation, said typewriter having a carriage, said perforator operable in a cycle of punching operations for which a typing operation with an accompanying advance of said carriage is preparatory and precedent, of means becoming effective during and as a result of said cycle, whereby said typewriter-carriage is automatically returned.

35. The combination with a typewriter and a card-perforator coupled for joint operation, said typewriter having a letter-feeding carriage and a carriage-return controller actuatable to cause engagement of carriage-return mechanism, said perforator having a trip-member actuatable to initiate an operating cycle of said perforator, of a key on said typewriter, linkage whereby said key may operate said perforator-trip-member, and linkage whereby said perforator during a cycle may actuate said carriage-return controller to effect return of said carriage.

36. In a typewriter and perforator coupled for joint operation, the combination of a typewriter-carriage, a perforator-carriage, means connecting both carriages for simultaneous letter-spacing and punch-indexing movements respectively, a driver effective for returning both carriages at the end of each line of operation to their initial positions, a clutch effective when closed to engage said driver with the carriages, a mechanism for operating said perforator to perforate a card, and means responsive to said mechanism effective to close said clutch and initiate the return of the carriages upon the completion of a card-punching operation.

37. In a typewriter and perforator coupled for joint operation, the combination of a typewriter-carriage and a perforator-carriage, means mechanically connecting said carriages for simultaneous movement, means for returning said carriages to normal positions upon the completion of each line of operation, a driving mechanism for actuating the perforator to punch a card, a clutch be-

tween the mechanism and the perforator, normally out of engagement therewith, means for throwing said clutch into and out of engagement to control the operation of said perforator, and means responsive to the final movement of said clutch as it is being thrown out of engagement to initiate the return of both carriages to initial positions.

38. A machine including perforating mechanism, typing mechanism including a carriage and a carriage-return mechanism, a key for controlling the last-named mechanism, a rotary clutch-device for actuating the perforating mechanism to punch a card in response to said key, means responsive to said clutch to automatically initiate the operation of said carriage-return mechanism upon the completion of one revolution of the clutch, and a motor effective in response to said means to return said carriage to its initial position in the machine.

39. In a perforating machine having a plurality of punches, a set of keys to select the same, a carriage including punch-indexing units responsive to certain of said keys, punching mechanism operative through a cycle of movements to punch a card according to the indexed punches, a driving device therefor, normally disconnected therefrom, a clutch for effecting connection of the driving device with said punching mechanism under the control of one of said keys, said clutch actuating a system of linkages to automatically initiate the return of said carriage upon the completion of said cycle, and means to return the carriage to its initial position in response to the movement of said linkages.

40. In a typewriting machine and a perforating machine, coupled for joint operation, a letter-feeding typewriter-carriage, a perforating machine carriage, power-driven carriage-return mechanism, and a single typewriter means effective to initiate a punching movement of said perforating machine and a return movement of both of the carriages by said mechanism.

41. In a typewriter including a set of keys and a perforating machine coupled therewith for joint operation and controlled by said keys, a letter-feeding typewriter-carriage, a power-return drive for the same, and a single key, included in said set, to control the perforating operations of said machine and the return movement of the typewriter-carriage concomitantly.

42. A typewriting and card-perforating machine having carriages coupled for joint feeding movements and return movements, said machine including a perforating mechanism having a cycle of operations for which the typing of a line of data is preparatory and precedent, a trip-member of said card-perforating mechanism actuatable to cause the initiation of an operating cycle thereof, a key on said machine, a train of linkages, mechanically connecting said key and trip-

member, whereby the key controls the initiation of said operating cycle of the perforating mechanism, and means responsive to the movements of said perforating mechanism at the completion of its cycle to initiate the joint carriage-return movements in predetermined sequence with reference to said operating cycle of the perforating mechanism.
